UNITED STATES PATENT OFFICE.

CHARLES O. STERLING, OF WASHINGTON, DISTRICT OF COLUMBIA.

DESIGN FOR A WHIP-SOCKET FOR AUTOMOBILES.

No. 37,951.

Specification for Design.

Patented April 10, 1906.

Application filed February 6, 1906. Serial No. 299,842. Term of patent 3½ years.

To all whom it may concern:

Be it known that I, CHARLES O. STERLING, a citizen of the United States, residing at Washington, in the District of Columbia, have invented a new, original, and ornamental Design for Whip-Sockets for Automobiles, of which the following is a specification, reference being had to the accompanying drawing, forming a part thereof.

The figure is a perspective view of a whip-

socket for automobiles, showing my new design.

I claim—

The ornamental design for a whip-socket for automobiles as shown.

CHAS. O. STERLING.
